(57) **CLAIM**

The ornamental design for an extrusion welding machine, as shown and described.

DESCRIPTION

FIG. 1 is a perspective view of an extrusion welding machine showing our design;

FIG. 2 is a left side elevational view thereof, the right side being a mirror image without handgrip;

FIG. 3 is a top plan view thereof;

FIG. 4 is a bottom plan view thereof; and,

FIG. 5 is a rear elevational view thereof.

The broken lines in the figures are environmental and form no part of the claimed design.
